UNITED STATES PATENT OFFICE.

GEORGE J. NETH, OF DAYTON, OHIO, ASSIGNOR TO THE EGRY REGISTER COMPANY, OF DAYTON, OHIO, A CORPORATION OF OHIO.

AUTOGRAPHIC REGISTER.

Application filed May 27, 1922. Serial No. 564,191.

My invention relates to autographic registers.

It is an object of my invention to provide an autographic register which will perfectly align the several sheets therein and re-align those sheets at each operation prior to the writing upon the sheets.

It is a further object to provide the maintenance of those sheets in stationary arrangement after being aligned so that as the writing takes place before the duplication of the record and during the making of the record there will be no shifting of the recording sheets.

15 It is an additional object to provide means for drawing the sheets out as a unit when being ejected which will prevent the sheets from becoming torn or the holes in the sheets from tearing.

20 It is a further object to provide sheets with the minimum of apertures therein for aligning purposes and sheets provided with such aligning apertures at points remote from the margin and remote from one 25 another so that the sheets will not be weakened by the apertures therein.

It is an additional object to provide such aligning apertures that the inequalities in the sheets, both longitudinally and laterally, 30 may be compensated for and the sheets properly aligned.

Referring to the drawings:

Fig. 1 is a side elevation of my register;

Fig. 2 is a front elevation of the register 35 from the ejecting end showing the ejector just preparatory to ejecting the sheets;

Fig. 3 is a top plan view of the register with the parts in position, similar to that in Fig. 2;

40 Fig. 4 is a bottom plan view of the operating mechanism as mounted on the cover;

Fig. 5 is a detail of the actuating means and unlocking means for the wrapper of the ejector taken on the line 5—5, viewed in the 45 direction of the arrow in Fig. 1;

Fig. 6 is a section on the line B—B of Fig. 5, showing the parts in the position shown in Figs. 1 and 3;

Fig. 7 is a section on the line B—B of 50 Fig. 5, showing the parts in the position just prior to the ejection of the sheets;

Fig. 8 is a section on the line C—C of Fig. 3, showing the oscillating mechanism for oscillating the positioning pins to locate 55 them in the apertures in the sheets;

Fig. 9 is a section on the line D—D of Fig. 3 showing the parts in the position of Figs. 1, 2 and 3;

Fig. 10 is a section on the line D—D showing the parts in the position just prior to 60 the ejection of the sheets with the sheets wrapped around the wrapper members;

Fig. 11 is a plan view of the ejecting end of the writing table;

Fig. 12 is a plan view of the arrangement 65 of the apertures in the sheets and their method of location;

Fig. 13 is a vertical sectional view taken on the line 13—13 of Fig. 14 and looking in the direction of the arrows, showing the 70 sheets of paper moved from writing to ejected position ready to be released.

Fig. 14 is an enlarged detail sectional view taken on the line 14—14 of Fig. 1 showing the sheets or webs of paper in relation 75 to the carbon sheets and the location of the carbon supply.

Referring to the drawing in detail, there will be seen as in Fig. 1, a conventional autographic register having a base plate 1, side 80 or frame members 2 in which are journaled on suitable axles the rolls of paper 3, 4 and 5. 6 is the container for the carbon paper 6^a which is wound on a roll 6^b and passed transversely between the sheets of paper in the conventional manner, being held on the other side of the writing table by any one of the well known means in the autographic register art, such as a bar 6^c carrying pins 6^d adapted to enter apertures in the sidewall 85 of the register. The roll 6^b is carried by a shaft 6^e which is retained in position in the container by a catch 6^f, the spring 6^g serving to hold the catch in operative position. The roll of carbon paper is engaged at its end in 90 the rear of the container by a spring-pressed plate or washer 6^h to keep it in proper alignment with the writing table.

Mounted upon the side members 2 and 100 pivotally connected thereto through the bolt 7 is a cover 8 having a cutaway portion as at 9 through which the sheets to be written upon are exposed. These sheets are supported upon the writing table 10 which may be permanently or detachably affixed to the 105 register as may be desired. The cover 8 is maintained in position through the latching fingers 11 pivoted at 12 to the forward portion of the side frame 2. Any desired means of accomplishing this may be employed. 110

It will be understood that the sheets 13, 14 and 15 are conveyed over the writing table beneath the cover and out the ejecting end of the machine, while the carbon leaves 5 are inserted between these webs of paper for the usual duplication of the autographic record written on the top sheet.

These sheets of paper have successive forms, usually duplicates, printed upon them. 10 These forms must be brought to register so that the writing on the top sheet will be duplicated in the exact spaces on the bottom sheets.

In preparing this paper for insertion in 15 this autographic register the rolls of paper are printed independently of one another and locating marks are printed on each set of forms to locate the area in which the positioning apertures must be punched. There 20 is, therefore, a definite relationship established between the positioning apertures and the forms because of the fact that the printing of the locating marks and the printing of the forms of any given roll transpires simultaneously. Varying conditions 25 of moisture and temperature may affect the paper but the relative movement by expansion or contraction of the paper will not affect the relative position of the forms and 30 the positioning marks and therefore the positioning apertures. The printing of the same forms and same positioning marks on different rolls does not affect the situation because this printing is equi-distant within 35 a reasonable degree between its respective parts and after the paper is mounted on the machine similar conditions of temperature and moisture will have a similar effect upon the paper within a reasonable degree, so that 40 the apertures having been located with respect to the forms in a definite relationship any changes that may take place in the paper will likewise change the positions of all of the forms and the change will be the 45 same relatively within a reasonable degree, satisfactory for all practical purposes.

When the sheets are so inserted in the machine tapering pins 16 and 17 will be inserted in the positioning apertures in the 50 paper and fit snugly therein. It will be understood that the pins are adapted to fit snugly when in the position shown in Fig. 2 or in Fig. 9 so that as they are inserted in the apertures in the paper the tapering body 55 of the pins will position all of the sheets relatively to the same location. As the sheets of paper are so thin they rest against substantially the same portion of the pin and are moved substantially the same distance when so positioned bringing them to 60 exact alignment. These pins are of different lengths and correspondingly of somewhat different taper, except that at the point where the sheets engage with the pins, the 65 pins are so tapered that the aligning effect

will be the same by either pin. The reason for making the pins of different length is that it facilitates the introduction of the pins in the holes when the wrapping bar is rotated about the point of its pivotal connection to the ejecting end of the machine just prior to the introduction of the pins in the apertures. This is not essential, however, but preferable.

At the time the pins 16 and 17 have been 75 inserted in the paper and the record is being made, the entire mechanism, known as the ejecting mechanism, is held stationary, as hereinafter set forth. This ejecting mechanism comprises a bar 19 carrying said pins 80 16 and 17 and a tube 26 to which the bar 19 is connected. The bar 19 is adapted to have the sheets of paper wrapped about it and the tube 26 serves to extend the bar 19 with the sheets wrapped thereabout beyond the register a predetermined distance, such distance being sufficient to feed one of the form lengths usually printed on such paper. The ejecting mechanism as a whole is held stationary in its normal position by a catch 20 90 extending over a lug 18 secured to one end of the bar 19. This catch freely rocks back and forth laterally about a pivotal point 21 on the side frame 2 and is constantly being moved toward the center of the machine by a weight 22. The bar 19 is rotatably mounted in a sleeve 42 constituting a part of a bearing 43 in which one end of the tube 26 is rigidly secured, whereby the movements of the ejector tube 26 will be imparted to the 100 rod 19. The tube 26 is guided in its movements by sleeves 23 and 24 secured to the under side of the register cover. After the sheets have been wrapped about the bar 19 and carried out of the machine by the ejector tube 26 they are released from the wrapping bar 19 and the ejecting mechanism as a whole is returned to initial position preparatory to issuing another form length, the lug 105 18 being again engaged by the catch 20 having a bevelled face 20a with which the lug 110 18 engages as the rod 19 is tilted on its return movement in the manner hereinafter set forth. However, before starting a second operation of the ejecting mechanism the sheets are severed by pulling them upwardly 115 against the cutting edge 30 of a blade 29.

The machine is locked against the ejecting movement through the mechanism shown in detail in Figures 5, 6 and 7 where 27 is a locking hook, the head 28 of which rests against the wrapping bar 19 to prevent its outward movement.

Mounted upon the bar 19 is an unlocking member 31 for the ejector rod 26. The outer 120 end of the member 31 at 32 comes in contact with the locking hook 27 upon the block 33 mounted thereon. This unlocking takes place when 32 depresses 33 due to the rotation of the bar 19 by the knurled head 34 125 130

which is splined to the reduced portion 39 of the bar 19, as shown at 35 and is adapted to slide laterally thereon against the resistance of the spring 36 which is contained between 5 the retaining head 37 and 34 in an aperture 38. This part 34 is known as the wrapper actuator. Prior to its being rotated it must be withdrawn and guided by 35 against 36, sliding laterally upon the reduced portion 10 of 19 which is designated as 39 in order to remove its locking lug 40 from a slot 41 cut in the sleeve 42 which is stationary with respect thereto. There are two slots 41. One slot serves the purpose of locking the 15 bar 19 in its wrapping position and the other serves to lock it in its aligning position. The sleeve 42 is mounted upon a supporting member 43 which constitutes the connection between the parts being discussed 20 and the ejector tube 26 which is journaled in the members 23 and 24 on the bottom of the cover 8.

Resisting this rotation of the bar 19 from the aligning position to the wrapping position 25 is a spring 44, one end of which is attached at 45 to the support 43 and the other end is attached to the pin 46 which is mounted upon 19 and turns with it. This spring thus constantly tends to restore 19 to 30 its initial aligning position and is only prevented from so restoring it by reason of 40 being in that slot designated 41 which positions 19 in its wrapped or wrapping position.

It will be understood that when this rotation 35 does take place against the resistance of the spring 44 that due to the rotation of the bar 19, the end 32 of the locking member 31 comes in contact with the block 33 and depresses the locking member 27 thus removing 40 the barrier of the head 28 of the locking hook 27 from the path of the outwardly moving bar 19.

The bar 19 has knurled surfaces 47 which engage with the paper when it is drawn 45 tightly about 19 by the pins 16 and 17 during the wrapping operation and serve as grippers to hold the paper throughout its width when it is moved outwardly to prevent any tearing of the paper against the 50 pins during the quick outward movement during ejection.

This locking member 27 is maintained normally in locking position by the spring 48 located on the bottom of the cover 8 (see 55 Fig. 4).

The ejector tube 26 is provided with a pusher 49 comprising a U-shaped member, the upper arm of which is adapted to ride above the top of the register cover, the lower 60 arm extending beneath the cover and terminating in a bearing 50^a to receive the end of the ejector tube 26 which is secured to said pusher by a screw 51. Projecting inwardly from this bearing 50^a is a finger member 50, 65 for the purpose presently to be described.

The bracket 25 is also attached to the tube 26 adjacent the bearing 50^a and supports a rod 52 adapted to release the wrapping means when in its extreme extended position, as hereinafter explained. The member 50 is adapted to frictionally engage a spring 53 secured to the under side of the cover of the register (Figs. 4 and 8). This spring forms a part of the means for rocking the ejector tube 26 and lifting the bar 19 70 to position the pins in the paper on the return movement of the ejecting mechanism. On top of the register cover I have provided a member 55 hinged thereto by a pin 56 and having steps 55^a. The end 54 of the 75 upper arm of the pusher 49 rides over these steps 55^a on the return of the ejecting mechanism which movement is permitted by the spring 53 just referred to, thus imparting the desired movement to the positioning pins to 80 cause them to enter and align the paper. When it is desired to again extend the ejecting mechanism to feed another form length the end 54 of the pusher 49 will pass under the member 55 and for this purpose the 85 member 55 is cut away, as shown at 55^b so that 54 will raise the member 55 on its hinge 56 and pass thereunder, after which the member 55 falls back into its normal position. The member 56 has bifurcated members 56^a secured to a tongue member 56^b by a pintle 56^c. This gives a hinge movement to the member 55. This member 55 is also given a rotary movement by means of a pin 56^d passing through the tongue 56^b and 90 mounted in the cover 8.

Returning again to Fig. 4 the finger member 50 also rides over a rib 57 which positions the several parts including the ejector tube 26 and the bar 19 so that the bar 19 is maintained at a position substantially parallel to the cover at all times until upon its return due to the fact that 54 rides upon 55, the bar 19 is tilted at an angle to the cover for the purpose of inserting the pins 16 to 17 into the apertures and dropping the wrapping bar 19 into a position where the lug 18 may be locked under 20 by sliding down upon the tapered head of the catch 20.

It will be understood that while the ejector tube 26 is guided by the sleeves 23 and 24 it is further guided by a rod 59 fastened at 58 to the register cover, the tube 26 telescoping said rod. The bearing 50^a on the pusher 49 secured to the end of the tube 26 also surrounds the rod 59 and serves to guide the tube 26 and accompanying mechanism in its movements to deliver from the register the desired amount of paper and re-engage and align the paper preparatory to feeding subsequent lengths of paper.

Referring to the rod 52 for unlocking the wrapping bar 19, this rod is mounted near its ends so that it may have a rocking movement and has secured at one end a pin 61 130

adapted to engage a cam surface on the lug 60 on the margin of the register cover when the ejecting mechanism has been extended to feed the desired amount of paper. At the 5 opposite end of the rod 52 adjacent the operating member 34 for the wrapping bar 19 is a pin 62 and when the rod 52 is rotated by the pin 61 coming in contact with the cam surfaced lug 60 the pin 62 will engage the 10 member 34 and move the lug 40 out of the notch 41. This will release the bar 19 which will then be rotated due to the action of the spring 44, whereupon the paper will be released from the bar 19 and drop off the pins 15 16 and 17, which at this time will be projecting downwardly. When the wrapping bar 19 is then returned with its pins to its initial position it will again fall into the apertures in the paper and pass through the cutaway 20 portions 64 in the writing table 10 which are provided for this purpose.

Operation.

In operation the sheets are properly drawn 25 forward over the writing table with the carbons interleaved between them and the pins 16 and 17 are inserted in the apertures positioning the sheets. After the record has been written upon the sheets the knurled member 30 34 is rotated after having been withdrawn to move 40 out of 41 and is rotated until 40 can drop into the other notch 41 against the resistance of the spring 44. In doing so the member 31 comes in contact through 32 with 35 33, depresses 27, moves 28 out of the road of the wrapping bar 19, rotates the wrapping bar 19 so that the paper is wrapped around it in engagement with the knurled surface 47, due to the action of the pins 16 and 17 in 40 the holes. The pusher 49 is then grasped and moved forwardly along the cover beneath the member 55 until the limit of movement is reached when the pin 61 will engage with the lug 60, rotate the rod 52, unlock 45 the handle member 34, permit the unwrapping of the paper and the dropping of the paper from the pins, whereupon, upon the return by the pusher 49 of the wrapping mechanism it will travel in a horizontal 50 plane until the portion 54 rides upon the member 55 when the pusher 49 will be tilted so that the pins can be inserted into new holes in the paper and by the several oscillations due to the steps on 55 the pins will be 55 inserted and positioned and the paper will be positioned on them. When the pusher 49 is moved beyond the member 55 the bar 19 will be returned to horizontal position and locked against outward movement by the 60 head 28 on the locking member 27 the lug 18 on the outer end of the bar 19 dropping beneath the catch 20 and further retaining the ejecting mechanism in normal position. It then is in such a position that it cannot be 65 moved in any direction. The paper is then

grasped and pulled upwardly against the cutter carried by 19 so that the copies upon which the records have been made can be severed from the machine.

While I have shown and described certain 70 features as constituting my invention, it will be understood that parts have been shown for purposes of illustration only, and that I do not desire to be limited to such details, as obvious modification will occur to persons 75 skilled in the art.

Having thus fully described my invention, what I claim as new and desire to secure by Letter Patent, is:—

1. In combination, in an autographic register, paper engaging means and wrapping means, and means for actuating said wrapping and engaging means to eject the wrapped paper.

2. In combination in an autographic register, a wrapping bar, means to wrap paper about said bar, and means to eject said bar with the paper wrapped thereabout beyond the frame of the register.

3. In an autographic register, ejecting mechanism to feed a predetermined amount of paper from said register comprising means to first wrap the paper and means to eject said wrapping means beyond the frame of said register, and means on said wrapping 95 means to engage said paper and prevent it slipping therefrom.

4. In an autographic register, ejecting mechanism to feed a predetermined amount of paper from said register comprising means to first wrap the paper and means to eject said wrapping means beyond the frame of said register, and means on said wrapping 100 means to engage said paper and prevent it slipping therefrom; said wrapping means 105 having means entering apertures in said paper to straighten the paper and assist in the wrapping of the paper.

5. In combination, in an autographic register, paper engaging means and wrapping 110 means, means for actuating said wrapping and engaging means to eject the wrapped paper, and means carried by said wrapping means to sever said paper.

6. In combination in an autographic register, a wrapping bar, means to wrap the paper about said bar, means to actuate said bar, means on said bar for engaging with the paper to prevent it slipping therefrom, means engaging in apertures in said paper 115 to straighten the paper and assist in the wrapping of the paper thereon, and means carried by said wrapping means to sever said paper.

7. In an autographic register, wrapping 120 means upon which paper is wrapped, paper engaging means to position the paper with respect to the wrapping means, actuating means for the wrapper, means to lock said wrapping means in wrapped position, means 125

- to move outwardly said wrapping means, means to unlock said wrapping means to permit the paper to be unwrapped therefrom, whereby upon the return of the wrapping means to its initial position, a new set of papers may be engaged for another ejection, means to lock the wrapping means and paper engaging means in the initial position, and means to unlock said locking means when the wrapping is accomplished. 70
8. In an autographic register, wrapping means upon which paper is wrapped, paper engaging means to position the paper with respect to the wrapping means, actuating means for the wrapper, means to lock said wrapping means in wrapped position, means to move outwardly said wrapping means, means to unlock said wrapping means to permit the paper to be unwrapped therefrom, whereby upon the return of the wrapping means to its initial position, a new set of papers may be engaged for another ejection, means to lock the wrapping means and paper engaging means in the initial position, means to unlock said locking means when the wrapping is accomplished, and means to prevent the transvers rocking movement of the wrapping means when in locked position. 85
9. In combination in an autographic register for sheets with apertures in predetermined positions therein, means to be inserted in said apertures to position the sheets relative to one another, wrapping means about which said sheets can be wrapped at one end, means on said wrapping means to engage with said sheets, actuating means for said wrapping means, means to lock said actuating means in the wrapping or unwrapping position, a yielding means to normally maintain said wrapping means in its unwrapped position, means on said wrapping means when actuated to its wrapping position to unlock said locking means, means to move outwardly said wrapping means with the paper, means to unwrap said paper from said wrapping means at the end of the stroke, and means upon the wrapping means being withdrawn to its initial position of tilting it and oscillating it in a vertical plane to reinsert the engaging pins and effect the alignment to the paper, and means to maintain said ejecting means and wrapping means in a predetermined horizontal position during ejection and retreat of the ejector to a predetermined point. 90
11. In an autographic register, means for engaging with positioning apertures in a plurality of sheets of paper, said means being tapered to bring the sheets of paper to register one over another with forms on said paper to be so registered longitudinally and laterally, the paper having printed forms and designations locating the positioning apertures, ejecting mechanism, and means to wrap the free ends of the sheets of paper around a part of said ejecting mechanism, whereby the paper may be positioned, held in position and ejected. 95
12. In an autographic register, means for engaging with positioning apertures in a plurality of sheets of paper, said means being tapered to bring the sheets of paper to register one over another with forms on said paper to be so registered longitudinally and laterally, the paper having printed forms and designations locating the positioning apertures, ejecting mechanism and means to wrap the free end of the sheets of paper around a part of said ejecting mechanism, whereby the paper may be positioned, held in position and ejected, and means carried by the ejecting and wrapping means by which, upon the return of the ejecting means and positioning means for a new alignment by inserting the positioning means in a new set of apertures, the ejected paper can be torn off. 100
13. In an autographic register, means for engaging with positioning apertures in a plurality of sheets of paper, said means being tapered to bring the sheets of paper to register one over another with forms on said paper to be so registered longitudinally and laterally, the paper having printed forms and designations locating the positioning apertures, an ejector, means to wrap the free end of the sheets of paper around said ejector, and means on the ejector for holding the paper in its wrapped position by contact with the paper through a plurality of points on the ejector, whereby the paper may be positioned, held in position and ejected. 115
14. In an autographic register, ejecting means, positioning elements, means to wrap the paper to be ejected around a part of the ejecting means, means to frictionally engage 120
- 55 60 65 70 75 80 85 90 95 100 105 110 115 120 125 130

- therewith, means to move outwardly said ejecting means, means to maintain said ejecting means in its horizontal position during ejection, means to unwrap the paper therefrom at the end of the stroke, and means upon the return of the ejecting means to oscillate the positioning means thereon for re-insertion in apertures in the paper being ejected.
- 10 15. In an autographic register, ejecting mechanism, tapered positioning means carried by said ejecting mechanism, said positioning means comprising members of different lengths, knurled surfaces on said ejecting mechanism for frictionally engaging with the surface of the paper, and means carried by said ejecting mechanism for severing the paper, whereby when the paper is ejected after having been positioned by the 15 positioning means and wrapped around a part of the ejecting mechanism the paper may be unwrapped, the ejecting mechanism returned and the paper severed by the severing means to the extent rejected.
- 20 25. 16. In an autographic register, ejecting mechanism, tapered positioning means carried by said ejecting mechanism, said positioning means comprising members of different lengths, knurled surfaces on said 30 ejecting mechanism for frictionally engaging with the surface of the paper, and means carried by said ejecting mechanism for severing the paper, whereby when the paper is ejected after having been positioned by the 35 positioning means and wrapped around a part of the ejecting mechanism the paper

may be unwrapped, the ejecting mechanism returned and the paper severed by the severing means to the extent rejected, and means for holding the ejecting mechanism in fixed 40 position while the severing takes place.

17. In an autographic register, a wrapping bar, means to wrap paper about said bar, means to actuate said bar with paper wrapped thereabout to feed a predetermined 45 length of paper from the register, and means carried upon said bar to sever said paper.

18. The combination in an autographic register, a wrapping bar, means to wrap paper about said bar, means to actuate the 50 bar with the paper wrapped thereabout to feed a predetermined length of paper from the register, means on said bar for engaging with the paper to prevent the slipping therefrom, and means carried by said bar to sever 55 said paper.

19. In an autographic register, paper engaging means, wrapping means upon which the paper is wrapped, actuating means for the wrapping means, means to lock said 60 wrapping means in wrapped position, means to move outwardly said wrapping means with the paper wrapped thereabout to eject a predetermined length of paper from the register, and means to unlock said wrapping 65 means to permit the paper to be unwrapped therefrom, whereby upon the return of the wrapping means to initial position a new set of papers may be engaged for another 70 ejection.

In testimony whereof, I affix my signature.
GEORGE J. NETH.
